US0D1020477S

(12) **United States Design Patent** (10) Patent No.: **US D1,020,477 S**
(45) Date of Patent: ** Apr. 2, 2024

(54) **CONTAINER FOR FLUIDS**

(71) Applicant: **Yildiz Dukkanı Kozmetik Pazarlama Sanayi ve Ticaret Anonim Sirketi, Istanbul (TR)**

(72) Inventor: **Eda Taspinar, Istanbul (TR)**

(73) Assignee: **YILDIZ DUKKANI KOZMETIK PAZARLAMA SANAYI VE TICARET ANONIM SIRKETI, Istanbul (TR)**

(**) Term: **15 Years**

(21) Appl. No.: **29/840,449**

(22) Filed: **May 28, 2022**

(51) LOC (14) Cl. **09-01**

(52) U.S. Cl.

USPC **D9/680; D9/553**

(57) **CLAIM**

I claim the ornamental design for a container for fluids, as shown and described.

DESCRIPTION

FIG. 1 is a perspective view of a container for fluids; FIG. 2 is a front view of the container for fluids; FIG. 3 is a left side view of the container for fluids; FIG. 4 is a rear view of the container for fluids; FIG. 5 is a right side view of the container for fluids; FIG. 6 is a top view of the container for fluids; and, FIG. 7 is a bottom view of the container for fluids. The broken lines depict portions of the container for fluids that form no part of the claim.

1 Claim, 3 Drawing Sheets
